CARRIER FOR BOTTLES

Roy E. Lowey, Evanston, Earl C. Potter, Chicago, and Charles B. Kilmer, River Forest, Ill., assignors to Container Corporation of America, Chicago, Ill., a corporation of Delaware

Application December 1, 1941, Serial No. 421,102

2 Claims. (Cl. 224—45)

The present invention relates to carriers for bottles and similar articles and more particularly to a collapsible form of carrier which can be made of foldable sheet material so as to be adapted for storage in collapsed condition prior to use.

One object of the present invention is to provide a collapsible carrier which can be formed from a minimum area of sheet material and which, when set up, will occupy an area substantially the same as the effective area of the group of bottles which the carrier is designed to hold.

Another of the objects is to provide a bottle carrier so constructed that it may be made from a single sheet of material without complete interruption of the sheet continuity, the only interruptions being those necessary to provide certain required apertures, slots and slits, thereby to reduce to a minimum the material required, the quantity of adhesive or other means needed to secure and hold parts of the sheet in position, and the amount of labor involved in other types of carrier.

Another important object is to provide a carrier of the character mentioned with integral tabs or the like so constructed and arranged as to aid in "setting-up" the carrier for the reception of bottles, to stiffen the carrier structurally in certain directions the better to resist stresses placed upon the carrier when in use, and to serve as buffer or cushioning means between the bottles, thereby to prevent direct contact between the bottles while in the carrier.

Still another object of the present invention is to provide a carrier of the type described having what may be termed a semi-telescoping or retractable handle portion which, when in extended position, will project above the tops of the bottles held in the carrier and which, when in retracted or telescoped position, will be disposed so that the upper edge of the handle will not project substantially above the tops of the bottles, whereby carriers with retracted handle portions may readily be stacked one upon the other for display or shipment.

A further object of the invention is to provide a form of carrying handle for paperboard bottle carriers which includes improved reinforcing means at the opening formed for insertion of the finger.

Other objects of the invention are generally to improve and to simplify and to make more rigid and durable, bottle carriers of the type described and so to arrange the material of the carrier as to provide a construction of maximum

strength and adaptability, the carrier to be constructed from folding sheet material, such as paperboard, having a minimum thickness.

In the drawings:

Fig. 1 is a perspective view of a carrier in set-up condition ready to receive bottles or similar articles;

Fig. 2 is a fragmentary sectional view taken along line 2—2 of Fig. 1;

Fig. 3 is a fragmentary sectional view taken along line 3—3 of Fig. 1;

Fig. 3a is a large scale detail view showing the manner and extent to which the blank is cut in forming a handle tab;

Fig. 4 is an end elevational view, partly in section, of stacked carriers, showing the handle element of the lower carrier retracted to a position permitting the top carrier to be stacked on the lower carrier;

Fig. 5 is a plan view of a form of the blank from which the carrier of the present invention may be made; and

Fig. 6 is a plan view of the assembled carrier in its collapsed condition.

The carrier, as herein disclosed, is adapted for quick assembly in the manufacturer's plant and for shipment in knocked-down or flattened condition to the bottling plant at which point it can be set up quickly and efficiently. The construction and arrangement are such that the carrier has no parts projecting appreciably beyond the contours of the bottles so that a plurality of the filled carriers may be deposited in a shipping container of a size which is substantially the correct size for retention of bottles not held in carriers.

While the carrier may be manufactured from a plurality of pieces of suitable material it is preferably made from a single continuous sheet or strip of foldable sheet material such as paperboard, and, generally speaking, comprises portions providing two bottle carrying compartments separated by a partition portion which projects upwardly between the compartments and a hand-grip, or carrier portion, extending upwardly from the partition portion to a suitable height which, preferably, is a short distance above the tops of the bottles that may be disposed in the carrier.

Referring more particularly to the drawings, the carrier, designated as a whole at 10, is shown as made from a single, continuous strip of foldable paperboard, the strip being suitably cut and scored, when blanked out, to provide handle panels 11 and 12, top panels 13, 13, side wall

forming panels, 14, 14, bottom panels 15 and 16, and a partition panel 17. A score line 18 is formed between the two handle panels so that the handle panels may be folded to lie one upon the other and thus provide a handle portion of double thickness.

The handle panels 11 and 12 are provided, respectively, with finger openings 20 and 21 formed by striking out tabs 22 and 23 which are adapted to be folded so as to clear the openings for the reception of the fingers of the person desiring to lift the carrier. The tab 23 in opening 21 is hinged along a score line 24 to the handle portion 11 and the tab 22 is hinged along a score line 25 to the handle portion 12, there being preferably an additional score line 26 formed in the tab 23 and spaced somewhat away from the score line 24 for the purpose of enabling the tab to be folded around several thicknesses of material. It should be noted particularly that the arcuate cuts or slits defining the ends of the handle tab 23 extend at least to points of tangency with the ends of score line 24, the better to permit the folding of the handle tab to its ultimate position. This last mentioned feature is well illustrated in Figs. 5 and 6 but also by the larger scale view of Fig. 3a.

As best shown in Fig. 1, the tab 22 is adapted to be folded upwardly to lie between the two handle panels 11 and 12 so as to provide for an increased thickness of material at the upper portion of the handle. The width of the tab 22 preferably is such that its free edge will snugly engage in the fold at the top of the carrier between handle portions 11 and 12. The ends 22a, 23a of the tab 22 are preferably formed so as to converge outwardly away from the line of hinge of the tab with the handle portion so that when the tab is folded upwardly inside of the handle the weight imposed upon the handle, when held in the hand, will be distributed over somewhat more of the handle than would be the case if the tab was formed with straight or perpendicular end edges. After the tab 22 has been folded upwardly, as indicated in Fig. 1 and the two handle panels brought down together, the tab 23 may then be folded through the opening 21 and can be folded around the upper edge of the opening 20 to conform with the triple thickness provided by the tab 22 and handle portions 11 and 12. The extra score line 26 enables the tab 23 to be effectively folded around in the manner just described, so that a broad bearing surface is presented to the hand for carrying the loaded carrier. By reference to Fig. 3a it will be observed that the length of the handle tab 23 is less than the corresponding dimension of the opening 20 provided by the displacement of the tab 22. This arrangement prevents the tab 23 from engaging and stressing the handle at the upper corners defining the opening 20 thereby reducing the chances of tearing the material at such corners.

Each of handle portions 11 and 12 is scored along lines 28, 29 and 30 for the purpose of providing corresponding panels 31, 32 and 33, the panels 31 and 32 being so related to the remainder of the handle portion as to enable the handle to be depressed or partly telescoped to a position where it will not extend above the plane of the tops of bottles disposed in the carrier. This is best seen by comparison of Figs. 1 and 4. Viewing Fig. 4 it will be observed that the bottom of another loaded carrier may be seated upon the

tops of the bottles in the lower carrier for support thereon.

After the two handle panels 11 and 12 have been brought together with tab 22 therebetween as illustrated in Figs. 2 and 6, staples 34, 34 may be driven through the end panels above the score or fold line 28 and staples 35, 35 may be inserted below the score or fold line 30 and in directions substantially parallel to other fold or score lines later described. This arrangement of inserting staples will leave the subpanels 31 and 32 free to swing about their common hinge line formed by the score lines 29, 29. Thus, by pressing the upper part of the handle so that the fold lines 28, 29 will move outwardly, the central portion of the handle may be moved down until the fold lines 28 will assume positions horizontally below the fold lines 29, 29. The width of the sub-panels 31 preferably is such that when bottles are held in the carrier it is possible for the hinge line 28 to move down so that the panels 31, 31 pass the horizontal, that is, are tilted downwardly as shown in Fig. 4, but the combined width of the panels 31, 31 is not so great that movement of the hinge 28, as just described, will be prevented. Such movement will, however, be resisted by the necks of the bottles and by the grip that the bottle carrying compartment of the carrier exerts upon the bottles to keep them in a vertical position. The widths of the sub-panels 31, 31 are made sufficient to offer an appreciable resistance when bringing these panels to a horizontal position, so that when the panels are moved downwardly beyond a horizontal position, the necks of the bottles will tend to force the panels to swing still further downwardly, and, in the same manner, will resist upward or return movement of the sub-panels 31 to a horizontal position. There is thus provided a construction which may be termed a toggle lock which will insure the retention of the upper part of the handle in downwardly collapsed position when it has been forcefully brought to such position past the dead center of the toggle which is the position of parts 31 when the sub-panels are both lying in a horizontal plane.

Each of the top panels 13, in the present instance, is formed with three bottle-receiving openings, the two outer openings being designated at 38, 38 and the inner or intermediate opening being designated at 39. The opening 38 is preferably shaped snugly to fit the bottles to be received therein. Each top panel at each side of the opening 38 is cut away from the panel 33 through the removal of pieces 40a and 40b (the full lines between and extending from pieces 40a and 40b indicating slits or cuts through the material), so as to provide down-folding flap elements 40, 40. To facilitate downward folding of these flap elements the top panel preferably is scored along lines 41, 41.

Preferably each of the flap elements 40, 40 is secured to the front panel 14 by what may be termed a bellows type connection so as to provide increased strength of construction and also to provide an arrangement for retaining the flap elements in downwardly disposed position in which position they cause retention of the carrier in set-up condition and also serve as dividing partitions and cushioning means between the inner and outer or adjacent bottles in each row. For this purpose there are also provided sections or parts 42, 42 in the front panel defined therefrom by fold lines 43, 43 and defined from the part 40 by fold lines 44, 44. Slits 45, 45 are

formed in the front panel to separate the lower ends of the sections 42 from the front panel.

By utilizing the construction just described, when it is desired to set up the carrier, the flap elements 40, 40 will be pushed downwardly while the top panels are brought to a position at an angle to the handle element. In practice, the pressure is applied along the fold lines 44 so as to cause the sections 42, 42 to fold inwardly and downwardly simultaneously with the downward folding of the flap elements 40.

The side marginal portions 46 which remain after removal of the pieces 40a and 40b and separation from flaps 40 by the slits or cuts connecting the openings formed by removal of the 15 said pieces are designed to embrace and give lateral support to the end or outside bottles disposed in the carrier and, to this end, each may be scored along score or fold lines 47 disposed at varying angles to one another. The exact angles at which the score lines 47 are disposed to one another or to the long edges of the portions 20 46 and the number of the intermediate score lines of each group thereof in each side marginal portion 46, are matters not relatively important so long as the side marginal portions may be so folded as to dispose parts of them more or less flat against the sides of the bottles disposed in openings or compartments 38, as best pictured in Figs. 1 and 4. However, in the embodiment illustrated the score lines 47 with one exception are shown as extending at angles of 45° and 90° to one another and to the long edges of portions 46; the one exception is that of an intermediate score line which is shown as making angles of approximately 120° and 60° with the edges of the portion 46, and which score lines may be omitted.

It will be noted that that score line 47 which is closest to a staple or fastener 35, is disposed at approximately 45° to the edge of portion 46 and that the staple 35 is so disposed as to extend substantially parallel and fairly close to that fold or score line, thereby aiding the marginal portions to bend to their proper bottle embracing positions. The arrangement of the marginal portions 46 as well as the arrangement of the down-turned flaps 40, with their holding sections 42, serves to give considerable structural strength against crushing, bending and other stressing forces and, together with the balance of the structure, provide a carrier of unusual quality.

One of the more important features of the invention lies in the arrangement whereby the carrier length is reduced to a point where it is substantially equal to the sum of the diameters of the bottles carried in a compartment, thereby minimizing the amount of material required to make the carrier, making a more compact package, and economizing on space required to pack or stack a plurality of loaded carriers. This feature is attained to a large extent through the arrangement of the top openings in the compartment and the construction about and defining such openings, and downturned flaps 40 together with segments 42 and the end pieces 46 and their formation providing the necessary structural strength as well as serving as retaining means and to cushion the bottles. The actual length of the bottle compartment may be defined, therefore, as substantially equal to the sum of the diameters of the bottles to be received in the compartment plus the product of the number of bottles or bottle openings in the compartment multiplied by the top wall material 70

thickness plus one thickness of the top wall material. For instance if there are to be three bottles in a compartment, the bottle diameters are 2½ inches each and the material thickness is $\frac{1}{8}$ " then the length of the carrier (back, bottom, front and top walls of each compartment) will be not substantially greater than $2\frac{1}{2}'' \times 3$ or $7\frac{1}{2} + (\frac{1}{8}'' \times 4 \text{ or } \frac{1}{8}'') = 7\frac{5}{8}''$.

The two bottle carrying compartments, one on each side of the partition panel 17, are held in position and to one another by glueing or otherwise securing a transverse marginal strip 48, segregated from bottom panel 16 by score or fold line 49, to the adjacent face of partition panel 17, so that the score line 49 lies parallel and adjacent to a score or fold line 50 segregating or differentiating panels 15 and 17.

When the carrier, as thus constructed is manufactured it will ordinarily be prepared and shipped to the user in "knocked-down" condition, that is, flat, and when it is ready for use it will be "set-up." In "knocked-down" condition the top and front walls of each bottle compartment will lie-in substantially the same plane and, respectively, against the back and bottom walls which, in turn, will lie in one plane, this arrangement being permitted by the dimensions of the walls and the score lines between panels 14 and 15 and panels 14 and 16. Also in the "knocked-down" state the carrier will have its handle tab 23 in the plane of panel 11. Accordingly, the carriers may be packed so as to utilize space in a most economical manner.

When the carrier is to be "set-up" for use it is a relatively quick and simple process. The bottle carrying compartment walls are moved into their proper positions in which they are shown in Fig. 1 and the flaps 40 and sections 42 are turned downwardly at right angles to the top walls in which positions they "lock" and are held, in turn holding the compartments in rectangular shape. The central parts of the side marginal portions 46 of the top walls may then be turned at right angles to the planes of the top walls and tend to hold such positions. So set up the carriers may be disposed beneath a bottle carrier loading machine for the automatic loading of bottles into all of the compartments, simultaneously if desired.

The foregoing description of what is at present considered a preferred embodiment of the invention is believed to be ample to enable anyone skilled in the art to reproduce and use the same as well as to appreciate the functions and purposes of the various parts. It will also be apparent that various changes and variations in the construction and arrangement of the carrier and its several parts may be effected and that adaptations of features of the invention to other constructions and for other purposes may be accomplished, all without departure from the spirit of the invention and the scope of the appended claims.

We claim:

1. A bottle carrier comprising, a handle portion and bottle receiving compartment, said bottle receiving compartment comprising two top panels extending outwardly from the handle portion, a side forming panel extending downwardly from the outer edge of each top panel, a bottom forming panel, and a back panel extending upwardly in line with and joined to the handle portion, each top panel being formed with three apertures for the reception of bottles, one of the end apertures being formed by cutting away a portion of the material of said top panel to leave

an end web of less width than a bottle diameter connecting the back panel with the side wall, said web being connected to the handle panel along a diagonal fold line extending upwardly and inwardly of the handle whereby the adjacent portion of the web may assume an angle to the plane of the top panel, said web having another diagonal fold line extending divergently from substantially the lower end of the first fold line toward said side panel, said web being connected to the side panel along a diagonal fold line extending outwardly and downwardly thereof, and said web being formed with an additional fold line diverging from the inner upper end of the third mentioned fold line, the mid-portion of the web between the second and fourth said fold lines being thereby disposable in a generally vertical position relative to the plane of the bottom panel, the said mid-portion of the web being resiliently held in such substantially vertical position, the end portion of the web tending to flex the adjacent portions of the side panel when the central portion of the strip is forced outward, whereby a bottle held in the opening between the web and the other edge of the opening will be gripped therein.

2. In a carrier of the character described formed from sheet material to provide a com-

partment adapted to receive two rows of bottles in upright position with their neck portions extending thereabove, said compartment including top, bottom and side panels and a partition panel extending substantially vertically between said rows of bottles and secured to said bottom and top panels, and a handle portion extending upwardly and substantially in the plane of said partition panel from the upper edge thereof and having its top edge normally substantially above the level of the tops of bottles disposed within said compartment, the improvement wherein said handle portion comprises two panels of said material in face-to-face relation, each of said handle portion panels being provided with at least three substantially horizontal spaced score lines at corresponding levels and said handle portion panels being secured in face-to-face relation above the uppermost and below the lowermost of said score lines, whereby the parts of said handle portion panels between said score lines may be deflected from face-to-face relation and the top of said handle portion may be depressed below the level of the tops of said bottles to allow a plurality of similar carriers filled with bottles to be stacked.
